UNITED STATES PATENT OFFICE.

WILLIAM B. WILLIAMSON, OF MELVERN, KANSAS, ASSIGNOR OF ONE-HALF
TO W. E. MYERS, OF POWHATTAN, KANSAS.

STAY FOR BUGGY-BEDS.

SPECIFICATION forming part of Letters Patent No. 704,769, dated July 15, 1902.

Application filed November 2, 1901. Serial No. 80,912. (No model.)

To all whom it may concern:

Be it known that I, WILLIAM B. WILLIAMSON, a citizen of the United States, residing at Melvern, in the county of Osage and State 5 of Kansas, have invented a new and useful Stay for Buggy-Beds, of which the following is a specification.

This invention relates to stays for buggy or wagon beds or boxes and the like; and the object of the same is to provide a strong and durable device of this class, having a light structure capable of reinforcing the corner and other joints of a wagon or buggy bed or box and requiring but a comparatively few 15 fastening devices to hold it firmly fixed in position.

The invention consists in the construction and arrangement of the several parts, which will be more fully hereinafter described and 20 claimed.

In the drawings, Figure 1 is a perspective view of a portion of a buggy-boot, showing the improved form of stay applied thereto. Fig. 2 is a transverse vertical section through 25 the stay and boot at the corner. Fig. 3 is an elevation of a modified form of the improved device.

Similar numerals of reference are employed 30 to indicate corresponding parts in the several views.

The numeral 1 designates the stay, which has sides 2 arranged at an angle to each other corresponding to that of the portion of the bed, boot, or wagon-box corner or joint to 35 which it is applied. The sides have opposite right-angular top and bottom end plates or members 3 continuous therewith and extending equally with the said sides to form partial end closures for the latter. The stay is preferably formed of metal having a thickness 40 about equal to that of sheet-iron or like sheet metal, and in view of the lightness of aluminium it will be used for the purpose. Other suitable thin material may be used, 45 however, and irrespective of the kind of material of which the stay is composed the angular ends or members 3 will form a part thereof and perform the advantageous function of strengthening the sides, as well as means for 50 receiving fastening devices, as shown by Fig. 2, and also conjunctively provide with the

adjacent portions of the sides complete corner coverings or protectors. When the stay is vertically arranged or so disposed that the ends or members 3 fit over the opposite terminals of the corner-posts of the boot, body, or box, the fastening devices can be driven through the same into the said posts, and thereby minimize the number of fastenings along the side edges of the sides 2, as clearly 60 shown by Figs. 1 and 2. It will also be understood that the stay may be applied in a horizontal position, and the ends or members 3 will similarly perform their function when so arranged and may be fastened to other 65 body structures aside from the posts mentioned.

At opposite terminals of the sides 2 and at intermediate points thereof transverse bracing-ribs 4 are located and integral with the 70 material of said sides, the said ribs meeting at the angle of the sides and serving to stiffen the stay and render it stronger without resorting to a cumbersome construction. The opposite end ribs form a part of the ends or 75 members 3 where they connect with the sides 2 and thicken the material at said points, so as to resist breaking at the corners.

The modified form of the device shown by Fig. 3 is similar in all general features of construction to the stay just described, and the difference of construction resides in the ornamental character of the braces 5, applied to the outer surfaces of the sides 2 and integral with the latter, the metal in this construction being cut away at intervals to lighten 85 the structure, and terminals, as at 6, extend completely to the edges of the said sides. The edges of the sides may be also suitably ornamented or given a pleasing configuration, 90 and changes in the size, surface form, and proportions may be resorted to without departing from the principle of the invention.

Having thus described the invention, what is claimed as new is—

1. In a device of the class described, the combination with a vehicle-body having a corner-post, of a stay comprising exterior sides arranged at right angles to each other to fit the corner of the vehicle-body and extending 100 from the top to the bottom of the same and provided with exterior bracing devices formed

integral with the sides, the inwardly-extending integral rectangular top and bottom plates entirely covering the space between the sides and connecting the latter and arranged on the corner-post and beneath the bottom of the sill of the vehicle-body and provided with perforations, and vertical fastening devices passing through the perforations and embedded in the corner-post, substantially as described.

2. In a device of the class described, the combination with a vehicle-body having a corner-post, of a stay comprising the vertically-disposed exterior sides conforming to the configuration of the corner of the vehicle-body and extending from the top to the bottom of

the same and provided with integral exterior bracing devices extending across the sides, the inwardly-extending integral top and bottom plates arranged in the same plane as the corner-post, and fastening devices passing through the top and bottom plates and embedded in the post, whereby the stay is adapted to bind the side and end to the post, substantially as described. ²⁰ ²⁵

In testimony that I claim the foregoing as my own I have hereto affixed my signature in the presence of two witnesses.

WILLIAM B. WILLIAMSON.
